UNITED STATES PATENT OFFICE.

JOHN ALWYN KELLER, OF BAY SHORE, AND CHARLES SPIELMANN, OF RICHMOND HILL, NEW YORK; SAID SPIELMANN ASSIGNOR, BY MESNE ASSIGNMENTS, TO SAID KELLER.

NUMBERING MECHANISM FOR TICKET-PRINTING MACHINES.

Application filed June 4, 1924. Serial No. 717,760.

To all whom it may concern:

Be it known that we, JOHN ALWYN KELLER, a resident of Bay Shore, in the county of Suffolk and State of New York, and 5 CHARLES SPIELMANN, a resident of Richmond Hill, in the county of Queens and State of New York, both citizens of the United States, have invented certain new and useful Improvements in Numbering 10 Mechanisms for Ticket-Printing Machines, of which the following is a specification.

This invention relates to numbering mechanisms for ticket-printing machines, and it has particular relation to an improved 15 mechanism for imprinting successive numbers upon the respective successive ticket units of a continuous ticket-strip as the latter is fed through the machine, the mechanism being operatively adapted to automatically adjust the imprinting numbers in 20 successive order at certain steps during the continuous operation of the machine, whereby the successive identifying numerical data is imprinted without manual adjustment.

25 The improved mechanism is adapted for use not only in printing successive numbers upon the ticket units of a continuous ticket-strip, such as clothing tickets which are to be attached to garments or other analogous 30 ticket-units for various purposes, but also for imprinting successive numbers in any adapted variable circumstances and requirements for use.

The object of our invention is to provide 35 an improved mechanism of the character set forth, which will possess advantages in point of convenience, positive automatic action, simplicity of construction, effectiveness and general efficiency.

40 In the drawings—

Figure 1 is a perspective view illustrating one embodiment of the improved mechanism.

Fig. 10 is a strip or diagrammatic illustration of the series of type-numbers as carried on the periphery of the type-wheel shown in Fig. 9. 65

Fig. 11 is a detail side view of one of the other type-wheels of the series.

Fig. 12 is a strip or diagrammatic illustration of the series of type-numbers as carried on the periphery of the type-wheel shown in Fig. 11. 70

Fig. 13 is a strip or diagrammatic illustration of the series of type-numbers as carried on the periphery of the main type-disc 75 which is common to all the type-wheels.

Corresponding parts in all the figures are denoted by the same reference characters.

Referring to the drawings, 14 designates 80 a suitable frame-work for carrying the operating mechanism. A main revoluble shaft, 15, has its bearing, as at 16, in said frame, and is mounted in projective position therefrom and adapted to be operated by any 85 suitable power connection. Said shaft carries a hub or collar, 17, fixed thereto, preferably by a set-screw, as at 18, and at its outer end said hub is provided with a circumferential flange forming an end disc, 90 19, preferably constituted by a circular disc-plate secured against the end of the hub 17 by screws, as at 20, and having a central opening corresponding to the bore of the hub. 95

21 designates an outer disc-plate having a central opening or bore by which it is mounted upon the main shaft 15. This outer disc-plate constitutes the main type-wheel, and together with the hub-disc 19 100 forms a boxing within which the supplementary general printing and control mech-

anism is operatively mounted and carried between said discs 21 and 19. Said discs are locked in fixed connection, and the locked connection is preferably afforded by 5 set-screws, as at 22, entering from the periphery of the hub-disc 19 and engaging the ends of stationary stub-shafts, 23, projecting from the inner face of the outer disc 21 into corresponding opening in the 10 hub-disc 19, the discs 19 and 21 being thus in fixed connection with an intervening space, as at 24.

The stationary stub-shafts 23, carried by 15 the outer type-disc 21, are equi-distantly arranged in circular series concentric to the axis of the main revoluble shaft 15 and disc 21 which moves therewith, and in the numerical arrangement of the imprinting type-numbers as comprised in the improved 20 mechanism as herein shown in the present embodiment of the invention ten of such stub-shafts are provided. The periphery of the main type-disc 21 is provided with a circumferential series of equi-distant type- 25 numbers, as at 25, which series, in said present numerical arrangement, runs consecutively from the numeral "1" to the numeral "0", said type-numbers being respectively in the plane of the center of the respective 30 stub-shafts 23.

Upon each of said stationary stub-shafts is revolvably mounted a type-wheel, as at 35 26, said type-wheels thus being in a circular equi-distant series concentric to the axis of the discs 21 and 19 which move with the main shaft 15. Said type-wheels 26 revolve between the discs 21 and 19 in the intervening boxing space 24, and each of said wheels comprises a body-disc, as at 40 27, adjacent the outer main type-disc 21, and a circular gear-disc, as at 28, carried at the inner face of said body-disc. The type-wheels 26, in their body-disc and gear, are each of uniform diameter, and their 45 body-discs are respectively provided at their periphery with a circumferential series of equi-distant type-numbers, as at 29, which are respectively adapted to come into alignment with the respective type-numbers 25 of the main disc 21 as said type-wheels 50 are revolved independent of the main type-disc 21. Thus, each type-number 25 of the main disc 21 has a respective type-wheel 26, the type-numbers of which latter are 55 brought successively into alignment with the respective type-numbers 25.

One of said type-wheels 26 constitutes 60 the automatic-trip type-wheel whereby the complete circular series of wheels are actuated in simultaneous step-movement. This trip-wheel is indicated at 30, (see Fig. 7), and carries a circular trip-gear, 31, extending beyond its main actuating gear-disc 28 in the longitudinal plane of its axis, 65 said trip-gear being projectively accommod-

dated in a corresponding recess, 32, in the periphery of the hub-disc 19, and its stub-shaft 23, upon which it revolves, being correspondingly extended, as at 33, said trip-gear 31 being thus projective beyond the 70 outer face of the hub-disc 19 towards the frame-work 14. In the present numerical arrangement, the trip-gear 31 has eight step-cogs respectively in alignment with the peripheral type-numbers 29 of its type-wheel 30—26.

The series of type-numbers 29 of all the type-wheels 26, except the wheel which is diametrically opposite the main trip type-wheel (26—30), run, in the present numerical arrangement, consecutively from the numeral "1" to the numeral "7" with a clear 80 peripheral space, as at 34, in compensation for the equi-distant succession of the type numbers, between the numerals "1" and "7", whereby the numerals "1" to "7" will be equi-distantly spaced and the clear double space 34 existing between "1" and "7" will be equivalent to the spaced position of another numeral such as if "8" were employed. 85 The type-wheel, indicated at 35, which is diametrically opposite the main trip type-wheel (26—30) is provided with the numeral "8", its series of numerals running consecutively from "1" to "8", without the 90 clear peripheral space 34 as on the other type-wheels.

To effect the uniform operation of all the circular series of type-wheels 26 in a co-incident step movement, under action of the trip-wheel 26—30, a circular gear-disc, 36, is mounted in common to the entire 100 train of type-wheel 26 and revolves upon an internal hub, 37, centrally carried at the inner face of the disc-plate constituting the main type-wheel 21, its geared periphery being in mesh with the gear-discs 28 of the 105 entire train of type-wheels 26 which are in concentric series with relation to said main gear-disc 36.

The step-movements of the train of type-wheels 26 and the main gear-disc 36 are controlled by a pawl and ratchet mechanism comprising a circular ratchet-plate, 38, carried at the face of the main gear-disc 36 towards the main disc type-wheel 21 and engaged by a spring-controlled pawl, 39, pivotally mounted upon the inner face of said disc type-wheel 21.

Said pawl and ratchet mechanism is thus 120 enclosed between the type-disc 21 and gear-disc 36, and the hub-bearing 37 of the disc 21 is shouldered, as at 40, and the central bearing-opening of the gear-disc 36 is correspondingly shouldered, as at 41, to position 125 the peripheral gear of the disc 36 in the plane of the gear-discs 28 of the type-wheels 26.

An opening, 42, may be provided through the main disc type-wheel 21, adjacent the 130

pawl 39, to enable the insertion of an instrument into engagement with the pawl to retain the same from engagement with its ratchet under conditions of adjustment of 5 the type-wheels 26 in the set of their peripheral type-numbers with relation to the type-numbers of the main disc type-wheel 21.

Projectively mounted upon the frame-work 14 is an arm, 43, adapted to engage the 10 peripheral step-cogs of the trip-gear 31 of the trip type-wheel 26-30, to actuate the latter in a step movement co-incident with one complete revolution of the main disc type-wheel 21. Said arm is provided with a 15 lateral finger, as at 44, at its terminal outer end, which is positionally projective with relation to the step cogs of said gear 31. The operative position of said trip-arm is fixed, but inasmuch as the arm will serve to 20 actuate the trip-gear 31 in either direction, so that the numbering mechanism can be operated in a reverse direction under such circumstances as may be desired, the arm is preferably adjustably mounted upon the 25 frame-work for positioning either in "forward" movement or "backward" movement. The preferred construction for turning and fixing the arm in said reverse operative position comprises a cylindrical bore, 45, in the 30 frame-work 14, in which bore the arm is turnably mounted and secured by a set-screw, 46, carried by the frame and entering said bore into engagement with the arm. The trip-arm also preferably carries a lat- 35 erally-projective finger, 47, serving as a pointer the end of which moves with relation to a segmental scale-line, 48, upon the face of the frame-work and having at one terminal the letter "F" indicating set for 40 "forward" movement and at the other terminal the letter "B" indicating set for "backward" movement. The pointer-finger 47 is preferably detachably mounted upon the trip-arm 43 by a body-eye receiving the 45 arm and carrying a set-screw, 49, engaging the arm.

It will be understood that the ticket-strip or other data to be numbered is fed beneath the type-wheels between the peripheral numbers thereof and a suitable underlying platen or bed, as indicated at 50.

The extension stub-shaft 23 of the trip type-wheel 26-30 is preferably detachably secured to the main disc type-wheel 21, for 55 purposes of strength, by having its outer end passing through a shouldered opening, 51, in the latter and secured by a nut, 52, set against the outer face of the disc 21.

The operation and advantages of our in- 60 vention will be readily understood by those skilled in the art to which the improved mechanism relates. In the numerical ar- 65 arrangement herein shown in the present embodiment of the invention, the mechanism is adapted to imprint numbers consecutively

from "1" to "80", the initial position of the type-wheels being such that the peripheral numeral "5" of the main disc type-wheel 21 is at the top and its peripheral numeral "0" is at the bottom, it being 70 understood that the trip type-wheel 26-30 is carried in alignment with said numeral "5" and the diametrically-opposite type-wheel 26-35 having the numeral "8" as hereinbefore described is carried opposite 75 said numeral "0". In such initial position, the complete train of ten co-acting type-wheel 26, except the bottom wheel 26-35, have their clear peripheral space 34 in alignment with the peripheral numbers 25 of the main 80 disc type-wheel 21, while the numeral "8" of said bottom type-wheel 26-35 is in alignment with the numeral "0" of said disc-wheel 21. Then, in the revolution of the 85 complete mechanism carried by the main shaft 15, the main disc type-wheel 21 in one complete revolution will imprint the numbers "1" to "9" successively, starting with the numeral "1", the trip-arm 43 being out of engagement with the trip-gear 31 of the 90 top trip type-wheel 26-30 at the commencement of the revolution of the main disc type-wheel 21 and the complete train of ten type-wheels 26 remaining stationary during said 95 imprinting action of the disc type-wheel 21. Then, when the initial revolution of the main disc type-wheel 21 brings its peripheral numeral "0" to the point of printing, and just before the imprinting action of said 100 numeral "0", the trip type-wheel 26-30 will have arrived at the top of the mechanism and the trip-arm 43 will actuate the trip-gear of said wheel 26-30 in one step movement in which each of the train of ten type-wheels 26 will be automatically moved 105 simultaneously, under actuation by the gear-disc 36 which is in gear connection common to said train, to bring their respective peripheral numerals "1" in alignment with the respective peripheral numerals of the main 110 disc type-wheel 21. The next number then imprinted will be "10", and in the ensuing revolution of the imprinting mechanism constituted by the main disc type-wheel 21 and the train of type-wheels 26 the numbers 115 "11" to "19" will be imprinted before the trip-arm 43 again operates to cause simultaneous movement of the train of type-wheels 26 to bring their respective numerals "2" in alignment with the respective peripheral numerals of the main disc type-wheel 21. Thus, in the successive step movements of the mechanism the numbers "1" to "80" will be imprinted, the final step 120 movement of the train of type-wheels 26 bringing the peripheral numeral "8" of the bottom type-wheel 26-35 in alignment with the peripheral numeral "0" of the disc type-wheel 21, while the clear peripheral spaces 34 between the numerals "1" and "7" of 125 130

the remaining nine type-wheels 26 of the train will be in alignment with the respective remaining peripheral numerals "1" to "9" of the main disc type-wheel 21.

- 5 When the imprint action to the number "80" is completed, the main disc type-wheel 21 and the train of type wheels 26 will again be in the initial position as before described, for imprinting the numbers "1" to "9" 10 successively before the trip-arm 43 again engages the trip-gear 31 of the top trip type-wheel 26-30 for the ensuing step movement of the train of wheels 26, under continued revoluble movement of the main shaft 15. 15 Thus, the improved mechanism, in the numerical arrangement herein shown, will imprint the numbers "1" to "80" in successive sets under automatic action in the continued revolution of the main shaft. 20 It will be understood that other numerical arrangements may be employed, as adapted to the relative action of the main type-wheel 21 and train of type-wheels 26, according to desired conditions and circumstances of use. 25

For a reverse movement in imprinting the succession of numbers provided by the mechanism, it is only necessary to set the trip-arm 43 at the "backward" point "B" 30 on the scale 48, when the engagement of its trip-finger 44 with the trip-gear 31 of the trip type-wheel 26-30, under reverse revolution of the main shaft 15, will cause a simultaneous step movement of the train of 35 type-wheels 26 in a reverse direction relative to the reverse movement of the main disc type-wheel 21 which is carried by the main shaft.

The improved mechanism is exceedingly 40 compact and affords certain and direct automatic action for continuous and successive imprinting of numbers within the range of its numerical arrangement without manual adjustment, and the positive inter-gear of 45 the step-moving printing elements precludes any liability to disarrangement. The step-moving elements are also compactly enclosed and protected within the boxing or housing formed by and between the main 50 discs 21 and 19 which are interlocked and carried by the revoluble main shaft, and it will be noted that in the details of construction as herein shown the various parts are 55 separably so connected that the mechanism can be conveniently taken apart when desired, for purposes of substitution or inspection or other requirements.

We do not desire to be understood as limiting ourselves to the detail features of construction and arrangement as herein shown and described, as it is manifest that variations and modifications therein may be resorted to, in the adaptation of our invention to varying conditions of use, without 65 departing from the spirit and scope of the

invention and improvements. We therefore reserve the right to all such variations and modifications as properly fall within the scope of our invention and the terms of the following claims.

Having thus described our invention, we claim and desire to secure by Letters Patent:

1. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, and means for simultaneously turning said series of type-wheels in step movements to alter their aligned type-numbers with relation to the type-numbers of said main wheel. 75

2. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, means for simultaneously turning said series of type-wheels in step movements to alter their aligned type-numbers with relation to the type-numbers of said main wheel, and trip means for actuating said series of type-wheels in their simultaneous step movement at pre-determined points in the revolution of said main type-wheel. 90

3. A numbering mechanism, comprising a main type-wheel having equi-distant type-numbers at its periphery, means for revolubly mounting said type-wheel, supplementary type-wheels revolubly mounted in series concentric to the axis of said main type wheel and respectively having at their periphery equi-distant type-numbers adapted to respectively align with the respective type-numbers upon said main wheel, said series of type-wheels being inter-gearied to move in unison, and means for actuating said inter-gear to simultaneously turn said series of type-wheels in step movements to alter their aligned type-numbers with relation to the type-numbers of said main wheel. 110

4. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their per- 125 130

riphery equi-distant type-numbers adapted to respectively align with the respective type-numbers upon said main wheel, said series of type-wheel respectively having uniform 5 gears, a main gear revolubly mounted within said concentric series of type-wheels and in mesh with all the respective gears thereof, and means for actuating said gear mechanism to simultaneously turn said series of type-wheels in step movements to alter their aligned type-numbers with relation to the type-numbers of said main wheel.

5. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, said series of type-wheels being inter-gearied to move in unison and one of said wheels having a supplementary trip-gear, and means for actuating said trip-gear to simultaneously turn said series of type-wheels in step movements to alter their aligned type-numbers with relation to the type-numbers of said main wheel.

6. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, said series of type-wheels being inter-gearied to move in unison and one of said wheels having a supplementary trip-gear, and trip means engaging said trip-gear at predetermined points in the revolution of said main type-wheel to actuate said inter-gearied series of type-wheels in a simultaneous turning step movement to alter their aligned type-numbers with relation to the type-numbers of said main wheel.

7. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, said series of type-wheels being inter-gearied to move in unison, and means for actuating said inter-gear mechanism of said type-wheels at predetermined points in the revolution of said main type-wheel to actuate said inter-gearied

series of type-wheels in a simultaneous turning step movement to alter their aligned type-numbers with relation to the type-numbers of said main wheel.

8. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, said series of type-wheels being inter-gearied to move in unison and one of said wheels having a supplementary trip-gear provided with peripheral step-cogs, and a fixed arm positioned to engage said step-cogs at predetermined points in the revolution of said main type-wheel to actuate said inter-gearied series of type-wheels in a simultaneous turning step movement to alter their aligned type-numbers with relation to the type-numbers of said main wheel.

9. A numbering mechanism, comprising a main type-wheel having equi-distant type-numbers at its periphery, means for revolubly mounting said type-wheel, supplementary type-wheels revolubly mounted in series concentric to the axis of said main type-wheel and respectively having at their periphery equi-distant type-numbers adapted to respectively align with the respective type-numbers upon said main wheel, said series of type-wheels being inter-gearied to move in unison and one of said wheels having a supplementary trip-gear provided with peripheral step-cogs, a fixed arm positioned to engage said step-cogs at predetermined points in the revolution of said main type-wheel to actuate said inter-gearied series of type-wheels in a simultaneous turning step movement to alter their aligned type-numbers with relation to the type-numbers of said main wheel, and means for altering the position of said fixed arm for reverse engagement of said step-cogs to actuate said inter-gearied series of type-wheels in a reverse movement with relation to a reverse revolution of said main type-wheel.

10. A numbering mechanism, comprising a main type-wheel having equi-distant type-numbers at its periphery, means for revolubly mounting said type-wheel, supplementary type-wheel revolubly mounted in series concentric to the axis of said main type-wheel and respectively having at their periphery equi-distant type-numbers adapted to respectively align with the respective type-numbers upon said main wheel, said series of type-wheels being inter-gearied to move in unison and one of said wheels having a supplementary trip-gear provided with peripheral step-cogs, a fixed arm turn-

ably adjustable and having a lateral pointer and positioned to engage said step-cogs at predetermined points in the revolution of said main type-wheel to actuate said inter-geared series of type-wheels in a simultaneous turning step movement to alter their aligned type-numbers with relation to the type-numbers of said main wheel, and an adjustment scale positioned with relation to said pointer of said arm, whereby the position of said fixed arm may be altered for reverse engagement of said step-cogs to actuate said inter-geared series of type-wheels in a reverse movement with relation to a reverse revolution of said main type-wheel.

11. A numbering mechanism, comprising a main type-wheel having equi-distant type-numbers at its periphery, means for revolvably mounting said type-wheel, supplementary type-wheels revolvably mounted in series concentric to the axis of said main type-wheel and respectively having at their periphery equi-distant type-numbers adapted to respectively align with the respective type numbers upon said main wheel, means for moving said series of type-wheels in unison, and a fixed trip-member positioned to engage and actuate said moving means of said type-wheels at predetermined points in the revolution of said main type-wheel to alter in step movements the aligned type-numbers of said supplementary type-wheels with relation to the type-numbers of said main wheel.

12. A numbering mechanism, comprising a main type-wheel having equi-distant type-numbers at its periphery, means for revolvably mounting said type-wheel, supplementary type-wheels revolvably mounted in series concentric to the axis of said main type-wheel and respectively having at their periphery equi-distant type-numbers adapted to respectively align with the respective type numbers upon said main wheel, means for moving said series of type-wheels in unison, a fixed trip-member positioned to engage and actuate said moving means of said type-wheels at predetermined points in the revolution of said main type-wheel to alter in step movements the aligned type-numbers of said supplementary type-wheels with relation to the type-numbers of said main wheel, and means for altering the position of said fixed trip-member for reverse engagement of said moving means to actuate said series of type-wheels in a reverse movement with relation to a reverse revolution of said main type-wheel.

13. A numbering mechanism, comprising a main revolvable shaft, disc members carried thereby and connected together with an intervening space, one of said members having equi-distant type-numbers at its periphery and constituting a main type-

wheel, supplementary type-wheels revolvably mounted between said disc members in series concentric to the axis of said shaft and respectively having at their periphery equi-distant type-numbers adapted to respectively align with the respective type-numbers upon said main wheel, means for moving said series of type-wheels in unison, and trip-means for actuating said moving means at pre-determined points in the revolution of said main type-wheel to cause the simultaneous turning of said series of type-wheels in step movements to alter their aligned type-numbers with relation to the type-numbers of said main wheel.

14. A numbering mechanism, comprising a main revolvable shaft, disc members carried thereby and connected together with an intervening space, one of said members having equi-distant type-numbers at its periphery and constituting a main type-wheel, supplementary type-wheels revolvably mounted between said disc members in series concentric to the axis of said shaft and respectively having at their periphery equi-distant type-numbers adapted to respectively align with the respective type-numbers upon said main wheel, each of said series of type-wheels having a uniform gear, a supplementary revolvable gear mounted within and in common to the circular series of type-wheels and engaging the respective gears thereof, and trip-means for actuating said inter-geared mechanism at predetermined points in the revolution of said main type-wheel to cause the simultaneous turning of said series of type-wheels in step movements to alter their aligned type-numbers with relation to the type-numbers of said main wheel.

15. A numbering mechanism, comprising a main revolvable shaft, disc members carried thereby and connected together with an intervening space, one of said members having equi-distant type-numbers at its periphery and constituting a main type-wheel, supplementary type-wheels revolvably mounted between said disc members in series concentric to the axis of said shaft and respectively having at their periphery equi-distant type-numbers adapted to respectively align with the respective type-numbers upon said main wheel, each of said series of type-wheels having a uniform gear, a supplementary revolvable gear mounted within and in common to the circular series of type-wheels and engaging the respective gears thereof, trip-means for actuating said inter-geared mechanism at predetermined points in the revolution of said main type-wheel to cause the simultaneous turning of said series of type-wheels in step movements to alter their aligned type-numbers with relation to the type-numbers of said main wheel, and means for locking said inter-

geared mechanism against movement in the interval between its step movements.

16. A numbering mechanism, comprising a main revoluble shaft, disc members carried thereby and connected together with an intervening space, one of said members having equi-distant type-numbers at its periphery and constituting a main type-wheel, stationary shafts fixed between said disc members in equi-distant series concentric to the axis of said main shaft, supplementary type-wheels respectively revolvably mounted upon said respective stationary shafts and respectively having at their periphery equi-distant type-numbers adapted to respectively align with the respective type-numbers upon said main wheel, means for moving said series of type-wheels in unison, and trip-means for actuating said moving means at predetermined points in the revolution of said main type-wheel to cause the simultaneous turning of said series of type-wheels in step movements to alter their aligned type-numbers with relation to the type-numbers of said main wheel.

17. A numbering mechanism, comprising a main revoluble shaft, disc members carried thereby and connected together with an intervening space, one of said members having equi-distant type-numbers at its periphery and constituting a main type-wheel, stationary shafts fixed between said disc members in equi-distant series concentric to the axis of said main shaft, supplementary type-wheels respectively revolvably mounted upon said respective stationary shafts and respectively having at their periphery equi-distant type-numbers adapted to respectively align with the respective type-numbers upon said main wheel, each of said series of type-wheels having a uniform gear, a supplementary revoluble gear mounted within and in common to the circular series of type-wheels and engaging the respective gears thereof, and trip-means for actuating said inter-geared mechanism at predetermined points in the revolution of said main type-wheel to cause the simultaneous turning of said series of type-wheels in step movements to alter their aligned type-numbers with relation to the type-numbers of said main wheel.

18. A numbering mechanism, comprising a main revoluble shaft, disc members carried thereby and connected together with an intervening space, one of said members having equi-distant type-numbers at its periphery and constituting a main type-wheel, stationary shafts fixed between said disc members in equi-distant series concentric to the axis of said main shaft, supplementary type-wheels respectively revolvably mounted upon said respective stationary shafts and respectively having at their periphery equi-distant type-numbers adapted to respective-

ly align with the respective type-numbers upon said main wheel, each of said series of type-wheels having a uniform gear, a supplementary revoluble gear mounted within and in common to the circular series of type-wheels and engaging the respective gears thereof, trip-means for actuating said inter-geared mechanism at predetermined points in the revolution of said main type-wheel to cause the simultaneous turning of said series of type-wheels in step movements to alter their aligned type-numbers with relation to the type-numbers of said main wheel, and means for locking said inter-geared mechanism against movement in the interval between its step movements.

19. A numbering mechanism, comprising a main revoluble shaft, disc members carried thereby and connected together with an intervening space, one of said members having equi-distant type-numbers at its periphery and constituting a main type-wheel, supplementary type-wheels revolvably mounted between said disc members in series concentric to the axis of said shaft and respectively having at their periphery equi-distant type-numbers adapted to respectively align with the respective type-numbers upon said main wheel, means for moving said series of type-wheels in unison, one of said series of type-wheels having a supplementary trip-gear projective beyond the disc member, and a fixed arm engaging said trip-gear at predetermined points in the revolution of said main type-wheel to cause the simultaneous turning of said series of type-wheels in step movements to alter their aligned type-numbers with relation to the type-numbers of said main wheel.

20. A numbering mechanism, comprising a main revoluble shaft, disc members carried thereby and connected together with an intervening space, one of said members having equi-distant type-numbers at its periphery and constituting a main type-wheel, supplementary type-wheels revolvably mounted between said disc members in series concentric to the axis of said shaft and respectively having at their periphery equi-distant type-numbers adapted to respectively align with the respective type-numbers upon said main wheel, each of said series of type-wheels having a uniform gear and one wheel of said series having a supplementary trip-gear projective beyond the disc member, a supplementary revoluble gear mounted within and in common to the circular series of type-wheels and engaging the respective gears thereof, and a fixed arm engaging said trip-gear at predetermined points in the revolution of said main type-wheel to cause the simultaneous turning of said series of type-wheels in step movements to alter their aligned type-numbers with relation to the type-numbers of said main wheel.

21. A numbering mechanism, comprising a main revoluble shaft, disc members carried thereby and connected together with an intervening space, one of said members having equi-distant type-numbers at its periphery and constituting a main type-wheel, supplementary type-wheels revolvably mounted between said disc members in series concentric to the axis of said shaft and respectively having at their periphery equi-distant type-numbers adapted to respectively align with the respective type-numbers upon said main wheel, each of said series of type-wheels having a uniform gear and one wheel of said series having a supplementary trip-gear projective beyond the disc member, a supplementary revoluble gear mounted within and in common to the circular series of type-wheels and engaging the respective gears thereof, a fixed arm engaging said trip-gear at predetermined points in the revolution of said main type-wheel to cause the simultaneous turning of said series of type-wheels in step movements to alter their aligned type-numbers with relation to the type-numbers of said main wheel, and means for locking said inter-gearred mechanism of the series of type-wheels against movement in the interval between its step movements.
22. A numbering mechanism, comprising a revoluble type-wheel having type-numbers at its periphery, and supplementary type-wheels mounted with relation to the peripheral type-numbers of said main wheel and in series concentric to the axis thereof, said series of type-wheels being revoluble independently of the revolution of said main wheel and respectively having peripheral type-numbers adapted to align with the respective type-numbers upon said main wheel.
23. A numbering mechanism, comprising a revoluble type-wheel having type-numbers at its periphery, and supplementary type-wheels revolvably mounted on and carried by said revoluble main wheel element and respectively positioned with relation to the respective peripheral type-numbers upon said main wheel, said series of type-wheels respectively having peripheral type-numbers adapted to align with the respective type-numbers upon said main wheel.
24. A numbering mechanism, comprising a revoluble type-wheel having type-numbers at its periphery, supplementary type-wheels mounted with relation to the peripheral type-numbers of said main wheel and in series concentric to the axis thereof, said series of type-wheels being revoluble independently of the revolution of said main wheel and respectively having peripheral type-numbers adapted to align with the respective type-numbers upon said main wheel, and means for automatically revolving said series of type-wheels at step-points during the revolution of said main wheel.
25. A numbering mechanism, comprising a revoluble type-wheel having type-numbers at its periphery, supplementary type-wheels revolvably mounted on and carried by said revoluble main wheel element and respectively positioned with relation to the respective peripheral type-numbers upon said main wheel, said series of type-wheels respectively having peripheral type-numbers adapted to align with the respective type-numbers upon said main wheel, and means for automatically revolving said series of type-wheels at step-points during the revolution of said main wheel.

In testimony whereof we have signed the foregoing specifications.

JOHN ALWYN KELLER.
CHARLES SPIELMANN.
